UNITED STATES PATENT OFFICE

ANDREW B. REAVIS, OF SWARTHMORE, AND RUDOLPH J. EISINGER, OF MOORES, PENNSYLVANIA, ASSIGNORS TO WESTINGHOUSE ELECTRIC AND MANUFACTURING COMPANY, A CORPORATION OF PENNSYLVANIA

GOVERNING MECHANISM

Application filed May 24, 1929. Serial No. 365,685.

Our invention relates to a control mechanism, more particularly to a control mechanism for a marine propulsion arrangement of the character set forth in the application of 5 W. B. Flanders, Serial No. 305,504, filed September 12, 1928, embodying a reciprocating engine exhausting to a low-pressure turbine, the latter having ahead and astern sections and also means for admitting high- 10 pressure motive fluid to the turbine for quickly reversing the direction of rotation thereof.

It is an object of our invention to provide a control mechanism for a reversible 15 prime mover, which control mechanism is responsive to the direction of rotation of the prime mover, and which admits motive fluid to obtain a predetermined speed of rotation in the desired direction. 20 A more specific object of our invention is to provide a control mechanism for the above mentioned marine propulsion arrangement, which automatically admits high-pressure motive fluid to the proper section of the turbine when the reversing mechanism of the 25 reciprocating engine is operated, and which continues to admit such motive fluid until a predetermined speed is attained in the direction for which the reversing mechanism is set.

In accordance with our invention we provide a gear pump which discharges fluid under pressure through one outlet when the turbine is operating in ahead direction and 30 through a second outlet when the turbine is operating in astern direction. When the reversing mechanism is set for operation in a given direction, the proper section of the turbine is placed under control of the fluid pressure from the corresponding outlet of the pump, and motive fluid is thus admitted to said section until the turbine is operating at a predetermined speed in the desired direction.

The above and other objects are effected by our invention, as will be apparent from the following description and claims taken in connection with the accompanying drawing, forming a part of this application, in which:

Fig. 1 is a diagrammatic view of a power plant having our novel control mechanism applied thereto;

Fig. 2 is a detail view of the pilot valve of the control mechanism positioned for 55 ahead operation; and

Fig. 3 is a similar view showing the pilot valve positioned for astern operation.

Referring now to the drawing more in detail, we show a multiple expansion reciprocating engine 10, driving a propeller shaft 11, having a propeller 12 connected thereto. High pressure steam from any suitable source, such as boilers (not shown), is supplied through a conduit 7. A conduit 8, connecting therewith, passes the steam to the inlet of the reciprocating engine, and interposed in the conduit 8 is a throttle valve 9 for controlling the supply of steam to the reciprocating engine. 60

Steam exhausted from the engine 10 is supplied by a suitable conduit 13 to a low pressure turbine 14. After energy is abstracted from the steam by the turbine 14, it is discharged to a condenser 15. The rotor 75 of the turbine is connected to a shaft 16, the latter entering the casing 17 of a suitable reduction gear and being connected to a pinion 18 meshing with the gear 19 carried by the shaft 11. The turbine 14 includes an 80 ahead section 20 and an astern section 21 so that the turbine is capable of operation in either direction to secure ahead or astern propulsion.

The exhaust conduit 13 from the reciprocating engine is connected to branches 23 and 24 leading, respectively, to the ahead and astern turbine sections 20 and 21. A high pressure steam line 25, communicating with the conduit 7, is provided with branches 26 90 and 27 leading, respectively, to the forward and astern sections 20 and 21.

Valves 41 and 41' are arranged in the branches 23 and 24, respectively, and such valves are operated by the reversing mechanism 33 of the reciprocating engine through interconnecting mechanism indicated generally at 32. The interconnecting mechanism includes, for example, a rod 87 connected to and operated by the reversing mechanism, 100

which has a lever 34 for this purpose. The mechanism 32 further includes, for example, bell crank levers 92 and 92' connected to the rod 87 and also to links 91 and 91', respectively, said links being connected to crank arms 42 and 42' with which the valves 41 and 41' are provided.

The admission of high pressure steam to the sections 20 and 21 through the branch 10 conduits 26 and 27 is controlled by our novel control mechanism, which is shown as of the fluid pressure type.

To obtain a governing fluid pressure which will control the admission of high-pressure steam to the turbine 14 until the turbine has attained the desired speed in the desired direction, a gear pump 43 is provided, said pump being driven by the turbine 14 in any suitable manner, at a speed proportional to 20 the speed of the turbine, and in a direction determined by the direction of rotation of the turbine shaft. The gear pump is so arranged that when the turbine is rotating in ahead direction, fluid under pressure is transmitted 25 to a conduit 44, and when the turbine is operating in astern direction, the pump passes fluid under pressure to a conduit 45.

A reservoir 46 contains a body of any suitable liquid, preferably lubricating oil, and a 30 conduit 47 communicates with the bottom thereof. The conduit 47 communicates with the conduits 44 and 45, at points near the gear pump 43, through the branch conduits 48 and 49, respectively. Check valves 51 and 35 52 are provided in the branches 48 and 49, respectively, thereby permitting the gear pump to draw liquid from the reservoir 46, but preventing the loss of fluid pressure thereto.

40 A conduit 53, communicating with the conduit 44, has an adjustable restricted orifice 54 therein, and a conduit 55, communicating with the conduit 45, has an adjustable restricted orifice 56 therein. The conduit 53 45 communicates with the conduit 55 beyond the orifices, and the conduit 55 communicates with the reservoir 46. The orifices 54 and 56 permit the escape of excess liquid to the reservoir 46, imposing a pressure on the liquid, however, which is a function of the 50 speed of the gear pump 43. It will thus be seen that, when the turbine 14 is operating in ahead direction, the gear pump 43 provides a fluid pressure in the conduit 44 which is a function of its speed, and when the turbine is operating in astern direction, the gear pump provides a fluid pressure in the conduit 45 which is a function of its speed.

The supply of high pressure steam to the 60 ahead section is controlled by a valve 61 interposed in the conduit 26, and the supply of high pressure steam to the astern section is controlled by a valve 62 interposed in the conduit 27. The valve 61 is actuated by a 65 piston 63 operating in a cylinder 64. A

spring 65 biases the piston 63 to open the valve 61.

The valve 62 is operated by a similar piston 66 operating in a cylinder 67 and also biased to open the valve by a spring 68. A conduit 69 communicates with the cylinder 64 for supplying actuating fluid thereto, and a conduit 71 communicates with the cylinder 67 for the same purpose.

The supply of fluid pressure from the conduits 44 and 45 to the cylinders 64 and 67 for operating the valves 61 and 62, respectively, is controlled by a pilot valve 72, which, in turn, is actuated by the reversing mechanism 33 of the reciprocating engine 10 through the rod 87, a bell crank lever 88, and a link 89. The pilot valve 72 has piston portions 73, 74, 75 and 76, and operates in a cylindrical valve casing 77. The pilot valve 72 is shown in Fig. 1 in the position corresponding to neutral position of the reversing mechanism 33.

The conduits 71 and 69 communicate with the casing 77 at points intermediate the piston portions 74 and 75, but adjacent to these piston portions, respectively. The conduits 45 and 44 communicate with the valve casing 77 at points which are always in communication with the space between the piston portions 73 and 74 and between the piston portions 75 and 76, respectively. A conduit 78, which furnishes liquid pressure of a value sufficient to close either of the valves 61 and 62, communicates with the casing 77 at a central point, and is always in communication with the space between the piston portions 74 and 75.

A throttle valve 81 is preferably interposed in the conduit 25 between the conduit 7 and the branch conduits 26 and 27. This valve is actuated by a piston 82 operating in a cylinder 83. The piston 82 is biased in a direction to close the valve 81 by a spring 84, and the conduit 78 communicates at the lower end of the cylinder 83, admitting fluid pressure thereto in a direction to open the valve against the force of the spring 84. A stem 85 is screw-threaded through the upper end of the cylinder 83 and is adapted to operate the piston 82 against the fluid pressure by means of a handwheel 86 attached thereto.

The operation of this embodiment of our invention is as follows:

Assume the apparatus to be in ahead operation at normal or full speed. The throttle valve 9 is open and the reversing mechanism 33 is in ahead position in which the rod 87 is at the right-hand end of its travel. The link 91 is at the lower end of its travel and the links 91' and 89 are at the upper ends of their travel, the link 91 maintaining the valve 41 in open position to permit the exhaust steam from the engine 10 to pass to the ahead section 20 of the turbine, and the

rod 91' maintaining the valve 41' in closed position.

The link 89 holds the pilot valve 72 in its upper position, as shown in Fig. 2. The conduit 69 is in communication with the conduit 44, and fluid pressure from the gear pump 43 is, therefore, imposed on the piston 63 to close the valve 61. The conduit 71 is in communication with the conduit 78 which provides fluid pressure to close the valve 62.

In normal ahead operation, therefore, only exhaust steam from the reciprocating engine is admitted to the turbine and, therefore, the most economical operation of the apparatus is obtained.

Suppose now that it is desired to reverse the direction of operation. The throttle valve 9 is closed to shut off the supply of steam to the reciprocating engine. The reversing mechanism 33 is actuated by means of the lever 34 to astern position, the rod 87 being moved to the left and the links 91' and 89 being moved to lowermost position and link 91 to uppermost position. The throttle valve 9 is again opened. The valve 41 closes communication with the ahead section and the exhaust steam from the engine is passed to the astern section through the branch conduit 24.

The pilot valve 72 is also moved by the link 89 to lowermost position, as shown in Fig. 3, the piston portion 74 being disposed between the ports communicating with the conduits 71 and 78. The conduits 78 and 69 communicate through the space between the piston portions 74 and 75, and fluid pressure from the conduit 78 is, therefore, communicated to the piston 63 to retain the valve 61 in closed position.

The conduit 71, however, is placed in communication with the conduit 45, through the space between the piston portions 73 and 74, and as the turbine is still rotating in ahead direction, due to its inertia, there is no pressure in the latter conduit. The spring 68, therefore, moves the piston 66 to open the valve 62, and high pressure steam is admitted to the astern section of the turbine. This steam quickly brakes the speed of the turbine in ahead direction, and then quickly accelerates it in astern direction. As the turbine attains a predetermined speed in astern direction, the pressure developed by the gear pump in the conduit 45 acts on the piston 66 against the force of the spring 68 and shuts the valve 62.

When high pressure steam is admitted to either section of the turbine, its pressure is reduced before it acts upon the low pressure blading in the turbine. This may be accomplished, as is already known in the art, either by using the valves 61 and 62 as pressure reducing valves or by providing a special set of nozzles for this purpose.

During the period of reversing of the re-

ciprocating engine the flow of steam therethrough is limited by the speed at which the pistons move. Also, the rotor of the turbine has considerable inertia in the direction of its rotation prior to reversal. Hence, the prompt admission of high pressure steam to the proper turbine section serves to overcome rapidly the inertia of the turbine and to reverse it quickly.

The apparatus is now maintained in astern operation by the action of high pressure steam on the reciprocating engine, and the further expansion thereof in the astern section 21 of the low pressure turbine.

Assume now, that it is desired again to reverse and resume ahead operation. The throttle valve 9 is closed, the reversing lever 34 is moved to the right to move the reversing mechanism 33 to ahead position and to raise the pilot valve 72 to the position shown in Fig. 2, and the throttle valve 9 is again opened. In its raised position, the pilot valve 72 places the conduit 71 in communication with the pressure supply conduit 78, so that the astern high pressure steam valve 62 remains shut as long as the pilot valve is in this position. The conduit 69 for the ahead valve 61 is placed in communication with the conduit 44.

While the control mechanism is now set for ahead rotation, the inertia of the turbine causes it to continue to rotate in astern direction until the inertia of astern rotation is overcome. While it is still rotating in astern direction, the gear pump 43 discharges fluid to the conduit 45 and there is an absence of fluid pressure in the conduit 44, which has been placed in communication with the conduit 69. The spring 65, therefore, opens the ahead valve 61.

High pressure steam is admitted to the ahead section of the turbine for overcoming the inertia of astern rotation, and for accelerating the speed of the turbine in ahead direction as soon as astern rotation has ceased. The direction of operation of the gear pump 43 is reversed simultaneously with the reversal of rotation of the turbine, and provides pressure in the conduit 44 which increases with the speed of ahead rotation of the turbine. As the turbine attains a predetermined desired speed in ahead direction the fluid pressure developed in the conduit 44 by the pump 43 attains a value sufficient to close the ahead valve 61. The turbine then operates solely on exhaust steam from the reciprocating engine.

Should the auxiliary source of fluid pressure transmitted through the conduit 78 fail for any reason, the spring 84 would move the piston 82 to close the throttle valve 81, thereby shutting off all supply of high pressure steam to the turbine, which would otherwise be permitted, due to the action of the springs 65 and 68.

The speed which the turbine must attain before the supply of high pressure steam thereto is shut off, is determined by the adjustment of restricted orifice 54 in ahead direction and by the adjustment of the orifice 56 in astern direction. Either orifice may be adjusted to admit live steam, if desired in the normal operation.

It will thus be seen that the high pressure steam is automatically admitted to the turbine to obtain a quick reversal of the direction of operation, only a normal operation of the throttle valve and reversing mechanism of the reciprocating engine being necessary.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are imposed by the prior art or as are specifically set forth in the appended claims.

What we claim is:

1. The combination with a prime mover capable of operation in opposite directions, of a control mechanism therefor comprising a control device adapted to be set for operation in either direction, and means operative, when the prime mover is operating in the direction for which the control device is set, to provide motive fluid admission in response to speed of the prime mover for operation in said direction and, when it is operating in the opposite direction, to provide motive fluid admission independently of the speed for operation in the direction for which the control device is set.

2. The combination with a prime mover capable of operation in opposite directions and admission valve means for operation in each direction, of a control mechanism therefor comprising a control device adapted to be set for operation in either direction, means operative, when the prime mover is operating in the direction for which the control device is set, to provide speed responsive control of the admission valve means for operation in said direction and, when it is operating in the opposite direction, to provide opening of said last-mentioned admission valve means independently of the speed, and means for closing the other admission valve means.

3. The combination with a prime mover capable of operation in opposite directions and admission valve means for operation in each direction, of a control mechanism for said valve means comprising a control device adapted to be set for operation in either direction, and means responsive to the direction of rotation for closing the admission valve means providing operation in the direction for which the control device is set upon attaining a predetermined speed in said

direction and for maintaining substantially full opening of said valve at all speeds in the opposite direction of that for which the control mechanism is set.

4. The combination with a prime mover capable of operation in opposite directions and having an admission valve for operation in each direction, of a control mechanism therefor comprising means for controlling each valve in response to speed of the prime mover in the corresponding direction and maintaining the valve open at all speeds in the opposite direction, and means for selectively placing either valve under control of its control means and for closing the other valve.

5. The combination with a fluid pressure turbine having an ahead and an astern section and admission valves for the respective sections, of a control mechanism for said valves comprising means responsive to speed of the turbine in ahead direction for controlling the admission valve of the ahead section and responsive to operation in astern direction for maintaining said valve open independently of the speed, means responsive to speed of the turbine in astern direction for controlling the admission valve of the astern section and responsive to operation in ahead direction for maintaining said valve open independently of the speed, and means for selectively placing either valve under control of its respective control means and for effecting closing of the valve or valves not under such control.

6. The combination with a fluid pressure turbine having an ahead and an astern section and admission valves for the respective sections, of a control mechanism for said valves comprising means providing fluid pressure of a value adapted to effect closing of the admission valves, a gear pump driven by the turbine at a speed proportional thereto and developing fluid pressure varying with the speed of the turbine, said pump having an opening through which fluid pressure developed by the pump is delivered when the turbine is operating in ahead direction and a second opening through which fluid pressure developed by the pump is delivered when the turbine is operating in astern direction, and means for selectively placing either admission valve under control of the corresponding fluid pressure developed by the pump and the other valve under control of the first-mentioned fluid pressure for effecting closing of the valve, or placing both valves under control of the first-mentioned fluid pressure for effecting closing thereof.

7. The combination with a marine power plant embodying a reciprocating engine, reversing mechanism therefor, a low pressure turbine receiving partially expanded motive fluid therefrom and geared thereto, said turbine having an ahead and an astern section,

- means for admitting high pressure motive fluid to said sections and admission valves for controlling the admission thereof to the respective sections, of a control mechanism 5 for said admission valves comprising means operative when the turbine is not operating at a predetermined speed in the direction for which the reversing mechanism is set to open the admission valve of the section providing 10 operation in said direction.
8. The combination with a marine power plant embodying a reciprocating engine, reversing mechanism therefor, a low-pressure turbine receiving partially expanded motive 15 fluid therefrom and connected thereto, said turbine having an ahead and an astern section, means for admitting high pressure motive fluid to at least one of said sections and an admission valve or valves for controlling 20 the admission thereof to the respective section or sections, of a control mechanism for said admission valve or valves comprising means operative when the turbine is not operating at a predetermined speed in the direction for which the reversing mechanism is set to open the admission valve of the section providing 25 operation in said direction.
9. The combination with a marine power plant embodying a reciprocating engine having reversing mechanism, a low-pressure turbine connected to the engine and receiving motive fluid discharged therefrom, said turbine having ahead and astern sections, means for supplying high pressure motive fluid to 30 said sections and admission valves for controlling the admission thereof to the respective sections, of a control mechanism for said admission valves comprising means responsive to the operation of the turbine in ahead 35 direction for controlling the admission valve of the ahead section, means responsive to the operation of the turbine in astern direction for controlling the admission valve of the astern section, and means controlled by the 40 reversing mechanism for preventing opening of either valve except when the reversing mechanism is set for operation in the corresponding direction.
10. The combination with a marine power plant embodying a reciprocating engine having reversing mechanism, a low-pressure turbine connected to the engine and receiving motive fluid discharged therefrom, said turbine having ahead and astern sections, means for supplying high pressure motive fluid to 45 said sections and admission valves for controlling the admission thereof to the respective sections, of a control mechanism for said admission valves comprising means responsive to the operation of the turbine in ahead direction for controlling the admission valve of the ahead section, means responsive to the operation of the turbine in astern direction for controlling the admission valve of the astern section, and means controlled by 50 the reversing mechanism for preventing opening of either valve except when the reversing mechanism is set for operation in the corresponding direction.
11. The combination with a reciprocating steam engine directly connected to a driven shaft and having reversing mechanism and a turbine connected to the driven shaft and having ahead and astern sections, of an exhaust passage leading from the engine to the ahead section, a valve in the passage, a live steam passage for the astern section, a valve in the last-named passage, means for biasing the live steam valve to open position, means for holding the live steam valve closed while the reversing mechanism is set for ahead operation, means operative when the reversing mechanism is set for astern operation for moving the live steam valve in closing direction in response to increase in speed of the turbine in astern direction, and means responsive to operation of the reversing mechanism from ahead position to astern position to close the valve in the exhaust passage leading to the ahead section and to release 55 said holding means and vice versa.
12. The combination with a reciprocating steam engine directly connected to a driven shaft and having reversing mechanism and a turbine connected by reduction to the driven shaft and having ahead and astern sections, of an exhaust passage leading from the engine to the ahead section, a valve in the passage, a live steam passage for the astern section, a valve in the last-named passage, a spring for opening the live steam valve, pressure-operated means for closing the live steam valve, means for supplying a first pressure to the pressure-operated means when operating ahead, means for developing a second pressure in response to the turbine astern speed, and means responsive to operation of the reversing mechanism from ahead to astern position to close the ahead section valve in the exhaust passage, to release the first pressure, and to render the second pressure effective to close the live steam valve upon attainment of sufficient astern speed and responsive to operation of the reversing mechanism from astern to ahead to apply said first pressure to the pressure-operated means and to open the exhaust passage valve.
13. The combination with a reciprocating steam engine directly connected to a driven shaft and having reversing mechanism and a turbine connected to the driven shaft and having ahead and astern sections, of exhaust passages leading from the engine to the ahead and astern sections; valves in the passages live steam passages connected to the ahead and astern sections; valves in the live steam passages; means for biasing the live steam valves open; means for holding the astern live steam valve closed when the re-

versing mechanism is set for ahead operation and for holding the ahead live steam valve closed when the reversing mechanism is set for astern operation; means responsive 5 to the speed of the turbine ahead to close the ahead live steam valve and responsive to the speed of the turbine astern to close the astern live steam valve; and means responsive to 10 operation of the reversing mechanism from ahead to astern position to close the ahead exhaust valve, to open the astern exhaust valve, to release the holding means with respect to the astern live steam valve and to render such means effective with respect to 15 the ahead live steam valve, and to render the speed responsive means effective to close the astern live steam valve upon attainment of sufficient astern speed, and vice versa.

14. A governing mechanism for controlling 20 a prime mover capable of operation in opposite directions, said mechanism being responsive to the speed and direction of rotation of the prime mover and including a gear pump having one outlet through which 25 fluid under pressure is delivered only when the prime mover is operating in one direction and a second outlet through which fluid under pressure is delivered only when the prime mover is operating in the opposite direction, 30 a pressure-responsive element associated with each outlet and subjected to the fluid pressure delivered therethrough, means controlled by one of the pressure-responsive elements for controlling the prime mover for 35 operation in one direction, and means controlled by the other pressure-responsive element for controlling the prime mover for operation in the opposite direction.

15. The combination with a prime mover 40 capable of operation in opposite directions and admission valve means for operation in each direction, of a control mechanism for said valve means comprising a control device adapted to be set for operation in either direction, a gear pump driven by the prime mover, said pump having one opening through which fluid pressure provided by the pump is delivered when the prime mover is operating in one direction 45 and a second opening through which fluid pressure provided by the pump is delivered when the prime mover is operating in the other direction, and means for opening the admission valve means providing motive 50 fluid admission for rotation in the direction for which the control device is set when said gear pump is not discharging fluid through the opening corresponding to said direction.

16. The combination with a prime mover 60 capable of operation in opposite directions and admission valve means for operation in each direction, of a control mechanism for said valve means comprising a control device adapted to be set for operation in either 65 direction, a gear pump driven by the prime

mover, said pump having one opening through which fluid pressure provided by the pump is delivered when the prime mover is operating in one direction and a second opening through which fluid pressure provided by the pump is delivered when the prime mover is operating in the other direction, and means responsive to discharge of fluid through the opening of the gear pump corresponding to the direction for which the control device is set for controlling, in response to the speed of the turbine, the admission valve means providing motive fluid admission for operation in said direction. 70

17. The combination with a prime mover capable of operation in opposite directions and admission valve means for operation in each direction, of a control mechanism for said valve means comprising a control device adapted to be set for operation in either direction, a gear pump driven by the prime mover, said pump having one opening through which fluid pressure provided by the pump is delivered when the prime mover is operating in one direction and a second opening through which fluid pressure provided by the pump is delivered when the prime mover is operating in the other direction, and means responsive to discharge of fluid through the opening of the gear pump corresponding to the direction for which the control device is set for controlling, in response to the speed of the turbine, the admission valve means providing motive fluid admission for operation in said direction and for opening said admission valve means when there is no discharge through 85 said opening. 90

In testimony whereof, we have hereunto 95 subscribed our names this 17th day of May, 1929.
